DESIGN FOR A LADY'S HANDBAG FRAME

George Rosenberg, New Rochelle, N. Y.

Application January 31, 1939, Serial No. 82,691

Term of patent 7 years

To all whom it may concern:

Be it known that I, George Rosenberg, a citizen of the United States and a resident of New Rochelle, Westchester County, and State of New York, have invented a new, original, and ornamental Design for a Lady's Handbag Frame, of which the following is a specification, reference being had to the accompanying drawing, forming a part thereof, wherein:

Fig. 1 is a front elevation of a lady's handbag frame embodying my design and showing the same in closed position;

Fig. 2 is a side elevation of the handbag frame in closed position;

Fig. 3 is a plan view of the handbag frame in closed position;

Fig. 4 is a bottom view of the handbag frame in closed position;

Fig. 5 is a sectional view thereof taken approximately in the plane of the line 6—6 of Fig. 1, but showing the handbag frame in open position; and

Figs. 6, 7 and 8 show the configuration of the handbag frame section in closed position, taken respectively on the lines 6—6, 7—7 and 8—8 of Fig. 1.

The dominant features of my design reside in the portions shown in full lines.

I claim:

The ornamental design for a lady's handbag frame, substantially as shown and described.

GEORGE ROSENBERG.
